CLAIM

The ornamental design for a precious stone setting, as shown and described.

DESCRIPTION

FIG. 1 is a perspective view of a precious stone setting showing my new design;

FIG. 2 is a top plan view of FIG. 1;

FIG. 3 is a front view of FIG. 1, the rear view being symmetrical thereto; and,

FIG. 4 is a right side view of FIG. 1, the left side view being symmetrical thereto.

The broken lines in the drawings illustrate portions of the precious stone setting that form no part of the claimed design.
